(57) **CLAIM**

We claim the ornamental design for a mobile terminal, as shown and described.

DESCRIPTION

FIG. 1 is a front perspective view of a mobile terminal showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view, in which the mobile terminal is provided in a closed position; and,

FIG. 9 is a rear view of FIG. 8.

The broken lines in the figures show portions of the mobile terminal which form no part of the claimed design.

The dot-dash lines in the figures represent an unclaimed boundary line and form no part of the claimed design.
